METHOD OF HIGH-TEMPERATURE TREATMENT OF COMPOUNDS

Robert E. Stanton, Denver, Colo.

Application May 25, 1948, Serial No. 29,047

2 Claims. (Cl. 263—52)

1

This invention relates to heating and heat transferring apparatuses and it relates more particularly to a heating apparatus for promoting the reaction between hydrocarbons and other reactive compounds, the cracking of hydrocarbons and other chemical reactions. More particularly, it relates to an apparatus wherein pebbles, preferably formed of surface active materials and the like, may be more efficiently heated prior to delivery into a reaction chamber wherein they are used for promoting the reaction by heat transfer.

It has been suggested heretofore that ceramic pebbles and the like may be continuously fed through a furnace where they are heated and then delivered into a reaction chamber where they are used to heat materials supplied to the chamber. As the pebbles give up their heat, they are discharged continuously from the reaction chamber and returned to the top of the furnace to be reheated and delivered in a continuous stream into the reaction chamber.

The prior devices have not been very efficient in the heating of the pebbles for they have been designed primarily so that they are heated by contact with heated combustion products. Due to the fact that ceramic materials are poor conductors, contact with the heated gases is insufficient to raise them efficiently to a desired temperature throughout and to make the best use of the heat supplied to the heating furnace.

An object of the present invention is to provide a more efficient system of heating the pebbles in a device of the character described above so that more efficient use of the heat of combustion is obtained.

Another object of the invention is to provide a system wherein the pebbles are heated by radiant heat at about flame temperature as well as by contact with heated products of combustion.

Other objects and advantages of the process will become apparent from the disclosure of a typical apparatus embodying the present invention.

In accordance with the present invention, I have provided a heating and reaction system of the type described generally above wherein a fuel is introduced into and only partially burned in one or more muffles communicating with the interior of the furnace. The fuel and combustion supporting gas are supplied at a sufficiently high velocity to permit only part of the fuel to burn within the muffle, the remainder of the fuel flowing into the mass of pebbles within the furnace chamber to be burned in the interstices between the pebbles. In this way, the pebbles in the bottom of the furnace adjacent the outlets of the muffles are subjected to radiant heat of combustion at flame temperature while the pebbles above this combustion zone are preheated by the

heat of the combustion gases flowing upwardly through the body of pebbles.

It has been recognized that ceramic pebbles are, in themselves, somewhat surface active, and that the fuel will burn on surfaces of the pebbles. In this way, the fuel is burned very efficiently and the radiant heat at the surface of the pebbles raises their temperature very quickly. The pebbles so heated are delivered to the reaction chamber where they give up their heat and are recirculated, as described above.

For a better understanding of the present invention, reference may be had to the accompanying drawing, in which the single figure is a view in front elevation of a typical system embodying the present invention with the furnace or heating portion of the system shown partly in section and the reaction chamber shown in vertical section to disclose details thereof. The heating and reaction system disclosed in the drawing includes an elongated furnace shell or chamber 10 which may be provided with a steel jacket and a refractory lining. The lower end of the chamber 10 is provided with a tapered portion 11 which communicates by means of a passage 12 with the upper end of a reaction chamber 13. The reaction chamber 13 may consist of a steel or alloy shell which may be lined with refractory material, if desired. The pebbles flow from the furnace 10 through the passage 12 into the reaction chamber 13 and are discharged continuously from the latter through the restricted neck portion 14 onto an endless metal conveyor 15. The conveyor 15 delivers the pebbles into the bottom of an upright conveyor housing 16 where the pebbles are picked up by means of a bucket conveyor 16, delivered to the top of the furnace chamber 10 and discharged into it by means of a chute 17. The upper end of the furnace 10 is provided with a flue 18 for discharging of flue gases and may also be provided with a blow off valve 19.

The structure described generally above is substantially conventional. The novelty of the present apparatus resides primarily in the heating and burner elements for heating the pebbles in the furnaces. The heating system includes one or more muffles 20, each of which is provided with pear-shaped chamber 21 therein having enlarged outer end portion and narrow neck portion communicating with the interior of the furnace. The burner 22, through which fuel gas is supplied, extends into the enlarged portion of the chamber so that a part of the fuel is burned with the air supplied by means of the pipe 23 within the chambers 21. I have found that most efficient heating is obtained by maintaining the fuel gas and air velocities near or above the limit of flame propagation velocity so that only a minor portion of the fuel is actually

burned within the muffle chambers 21. In a typical installation, using methane as the fuel, the velocity of the gases may be about one foot per second. With other fuels, slightly higher or lower velocities may be used to permit ignition and combustion of the fuel. Preferably, the fuel and air are admitted substantially in the proportions which are required stoichiometrically for perfect combustion, thereby eliminating excess air which might produce an oxidizing atmosphere. For this reason, the mixture must be passed through the muffles and mixing valves if the fuel and air are mixed before introduction into the muffles, at a speed exceeding that of flame propagation to avoid spontaneous combustion or flash backs.

The unburned fuel flows into the furnace where the fuel-air mixture is burned directly in contact with the pebbles. It is highly important that the gaseous mixture should be burned within the interstices between the pebbles so that heat transfer can occur at approximately flame temperature. Inasmuch as certain refractory substances which are suitable for use as pebbles, such as, for example, alumina, silicon carbide, fire clay, etc., have the property of catalytically assisting combustion, it will be apparent that very efficient combustion of the fuel is obtained in this zone.

The combustion products are appreciably cooled after yielding a large part of their heat to the pebbles by radiant heat transfer. However, the heated combustion gases transfer additional heat to the pebbles by convection and contact. The rate and efficiency of the heat transfer to the pebbles depends upon the velocity of the flowing gases. On this account, the upper part of the furnace preferably is formed in such a manner as to provide a progressively decreasing cross-sectional area so that a relatively uniform gas velocity through the pebbles can be maintained despite the progressive decrease in gas volume due to cooling. This effect is produced by tapering the upper portion of the furnace chamber as shown in the drawings.

It has been found that, in the present system, the burning fuel yields up almost 65% of its total recoverable heat in the form of radiant heat and the remainder is in the form of convective heat. In this way, approximately 700 B. t. u. can be transferred for each pound of pebbles circulated in an hour if the rate of circulation is such that the entire pebble bed is circulated once every forty-five minutes. Pebble temperatures of 1600° F. can be readily attained by the use of the present system with great economy in the fuel burned.

The above-described system may be used for promotion of many different types of reactions, such as, for example, the production of carbon disulfide, as disclosed in my copending application Serial No. 29,046 filed May 25, 1948, the cracking of hydrocarbons and the reaction of hydrocarbons and other reactive compounds. As disclosed in my copending application Serial No. 29,046 a hydrocarbon gas such as methane may be introduced into the reaction chamber 13 through the manifold 24 while another reagent such as molten sulfur can be introduced into the mass of pebbles through the perforated pipes 25. If desired, the pebbles may be coated with a catalytic agent introduced through the nozzle 26 in the lower part of the furnace 10. Many other variations of the means for introducing the reagents will occur to those skilled in the art.

It will be understood that the system described above can be varied substantially in its capacity and that different kinds of fuel can be burned in the system. Therefore, the form of the invention described above should be considered as illustrative and not as limiting the scope of the following claims.

I claim:

1. A method of heating chemical compounds to promote reactions therebetween comprising continuously introducing ceramic pebbles into the top of a reaction zone from a heating zone above it, and returning the pebbles from the bottom of the reaction zone to the top of the heating zone, introducing air and fuel into a combustion chamber outside said heating zone at a velocity such that only a minor portion of the fuel is burned in the combustion chamber to heat the remainder of the air and fuel, discharging said remainder of the fuel, the combustion products and the air from the combustion chamber at a velocity above flame propagation velocity into said heating zone, said heating zone being of greater size than said combustion zone wherein the velocity of the fuel, combustion products and air are decreased and the fuel is burned in the interstices and at the surfaces of said pebbles to heat said pebbles at flame temperature.

2. A method of heating surface active ceramic pebbles for promoting chemical reactions comprising supplying surface active ceramic pebbles continuously to the top of a reaction chamber from a furnace above it, returning the pebbles to the top of the furnace from the bottom of the reaction chamber, supplying fuel and combustion supporting gas to a burner in a combustion chamber outside of said furnace and communicating with it through a restricted passage, the fuel and air being supplied to said burner at a velocity sufficiently below flame propagation velocity to burn only a part of said fuel in said combustion chamber and heat the remainder of the fuel and the gas, discharging said remainder of the fuel, the gas and the combustion products from the chamber through said restricted passage at a velocity above flame propagation velocity and burning said remainder of the fuel in the furnace in the interstices between said pebbles to heat them at flame temperature and thereby form additional combustion products flowing upwardly through said pebbles, and maintaining the velocity of the combustion products substantially constant as they flow upwardly through the furnace.
